BRACELET

Alfred Philippe, New York, N. Y.

Application July 23, 1936, Serial No. 92,262

15 Claims. (Cl. 63—1)

The invention relates to jewelry and is particularly adapted to the employment of ornamented faces or plates which may be employed for different purposes. Thus an ornamented plate 5 may have attached to it a hinged member so that it may be used as a clip. One or a plurality of such clips may be associated with and mounted on a bar carrying a pin so that the ornamented member or members may form a brooch 10 or the ornamented member or members may be mounted on or associated with a bracelet or a part thereof. Thus the same ornamented member may be used interchangeably for various purposes.

15 In the accompanying drawings Figure 1 is a side elevation of one form of bracelet on which is mounted ornamental members. Fig. 2 is a similar view of the bracelet from which the ornamental members have been removed. Fig. 20 3 is a rear plan view of one of the ornamental members showing the clip member in place and the means for attachment to the bracelet. Fig. 4 is a top plan view of the bracelet of Fig. 1 open for placing on the arm of the wearer, one 25 of the ornamental members being shown in dotted lines. Fig. 5 is an enlarged fragmentary plan view of the clasping portion of the bracelet. Fig. 6 is a longitudinal vertical section on the line 6—6 of Fig. 5. Fig. 7 is a fragmentary side 30 elevation of another specific form of bracelet. Fig. 8 is a top plan view of the bracelet of Fig. 7. Figs. 9 and 10 are front and top plan views of pin bars which may be associated with the ornamental elements.

35 Referring specifically to Figs. 1 to 6 of the drawings a bracelet may consist of two members 20 and 21 hinged at 22 and removably joined together at their other ends by a clasp member 23. If desired the members 20 and 21 may 40 be rigid. Although not essential these members where they join may be cut out as illustrated in the drawings leaving tongues 24 and 25 on the members 20 and 21 respectively. The end of the member 20 or its tongue 24 may be turned up- 45 ward as at 26 and then turned backward as at 27. The portion 27 may overlie the tongue 24 and be substantially parallel thereto. The tongue 27 may be slotted so that its arms may be resilient and on one side may be formed a lug or projection 28 for a purpose hereinafter explained. Likewise the end of the member 21 or its tongue 25 may be turned upwardly as at 50 29 and backwardly as at 30. The portion 30 may be positioned symmetrically with the portion 27 and may likewise be slotted and pro-

vided with a lug or projection 31. The portion 29 corresponds in general to the portion 26 but has projecting arms 32 which are deformed or pinched together slightly so that when the member 29 is pressed to the member 26 the arms 32 5 will engage the member 26 and spring around it so as to clasp together the tongues 24 and 25. Ornamental members, here illustrated as clips, may be carried by the members 27 and 30 in such a way as to substantially cover the ends of 10 the members 20 and 21 and conceal the portions cut out of their ends if they are cut out. Thus in Fig. 1 an ornamented clip 33 is illustrated in position on the member 27 and an ornamental clip 34 is illustrated in position on the member 15 30. As indicated in Fig. 3 each clip has on the back of its ornamental member a slot or groove 35 which is adapted to be passed over the member 27 or 30. The resiliency of the member will allow the lug 28 or 31 to be depressed during the 20 entrance and an opening or releasing stop 36 may be provided in one wall of the slot 35 to form a positioning stop for the lug 28 or 31. As indicated in Fig. 1 the clips are preferably positioned on the bracelet so that their adjacent 25 faces substantially touch.

In Figs. 7 and 8 is shown an alternative bracelet form in which a rigid member 40 of any suitable size is connected to flexible members 41 and 42 which are joined at their other ends by 30 a suitable clasp 43. A bar or plate 44 corresponding to the two members 27 and 30 of Fig. 2 is mounted on the rigid member 40 by means of a pillar or post 45 so that when the clips 34 are mounted on the bar 44 the hinged back clip 35 members 37 will lie between the bar 44 and the rigid plate 40.

In Figs. 9 and 10 is illustrated a bar 46 corresponding to the bar 44 and carrying a pin 47 and a clasp member 48 for the pin. The ornamented clip members 34 may be mounted on the bar 46 in the same way as on the members 27 and 30 and 44. It will be understood that because of the formation of the projection 28 or 31 and of its supporting member the support may be withdrawn from the slot 35 by exerting pressure which will be sufficient to cause the projection to slide away from or leave its seat and come out of the slot. There is no means provided for locking the bar in the slot and no means is needed. 45 The friction between the members is sufficient to hold it normally in place. The long contact between the bar end of the slot tends to hold the members against twisting or displacement and in proper position without the necessity of other 50 55

bracing, locking, supporting or positioning members or means.

It will thus be seen that the present invention provides a plurality of separate supporting members which may be used to carry the ornamental clip members so that a single pair of jeweled face plates may be worn either as clips or as a bracelet or as a brooch or the like.

The invention is not confined to the specific embodiment herein illustrated but may take other forms. The invention may be applied to other articles than bracelets.

I claim as my invention:

1. A bracelet comprising a rigid member, an upright member thereon extending away from the arm of the wearer, means carried by the last named member for carrying a clip brooch, said means lying substantially parallel with the rigid member.

2. A clip comprising an ornamental member and a member hinged thereto for attaching it to fabric, a groove on the back of the ornamental member, a bracelet, and means carried by the bracelet for engaging the groove so as to support the clip with the ornamental member exposed and the hinged member concealed.

3. A clip comprising an ornamental member and a member hinged thereto for attaching it to a fabric, a bracelet, and means on the bracelet to engage the clip so as to support it with the ornamental member exposed and the hinged member concealed.

4. A clip comprising an ornamental member and a member hinged thereto for attaching it to a fabric, a bracelet, and means on the bracelet to engage the clip so as to support it with the ornamental member exposed and the hinged member lying between the bracelet and the ornamental member.

5. A bracelet comprising two rigid members hinged together at one end and joined by a resilient catch at the other end, an ornamental member and means on each hinged member adjacent the catch to removably support the ornamental member.

6. A bracelet comprising two rigid members hinged together at one end and joined by a resilient catch at the other end, a clip and means on each hinged member adjacent the catch to removably support the clip.

7. A bracelet, a rigid member in the bracelet, flexible members attached to each end of the rigid member, means for joining the free ends of the flexible members to hold the bracelet about the arm of the wearer, and means carried by the rigid member for removably mounting a pair of clips thereon so as to conceal the rigid member.

8. A bracelet comprising two rigid members, a hinge joining the rigid members at one end, at the opposite end of one member a reduced portion having an extension turned outwardly and backwardly substantially parallel with the rigid member, at the opposite end of the other member a

reduced portion having an extension turned outwardly and backwardly substantially parallel with the rigid member, resilient members projecting from the last mentioned outwardly turned portion releasably engaging the first mentioned outwardly turned portion to close the bracelet about the arm of a wearer and bring the parallel portions substantially into contact, ornamental clips and means on the clips for releasably engaging the parallel portions.

9. A bracelet comprising a rigid member, an upright member thereon extending away from the arm of the wearer, and means carried by the last named member for carrying an ornamental member, said means lying substantially parallel with the rigid member and constituting the sole support for the ornamental member.

10. A bracelet comprising a rigid member, an upright member thereon extending away from the arm of the wearer, means carried by the last named member for carrying a clip brooch substantially parallel with the rigid member.

11. A clip comprising an ornamental member and a member hinged thereto for attaching it to fabric, a groove on the back of the ornamental member having an irregularity therein, a bracelet, and resilient means carried by the bracelet for engaging the irregularity in the groove so as to support the clip with the ornamental member exposed and the hinged member concealed.

12. A bracelet, a rigid member in the bracelet, a flexible member attached to the rigid member, and means carried by the rigid member for removably mounting a pair of clips thereon.

13. A bracelet comprising two rigid members, a hinge joining the rigid members at one end, at the opposite end of one member a portion turned outwardly and backwardly substantially parallel with the rigid member, resilient members projecting from the last mentioned outwardly turned portion releasably engaging the first mentioned outwardly turned portion to close the bracelet about the arm of a wearer and bring the parallel portions substantially into contact, ornamental clips, and means on the clips for releasably engaging the parallel portions.

14. A bracelet comprising a rigid member, an upright member thereon extending away from the arm of the wearer, means carried by the last named member for carrying an ornamental member substantially parallel with the rigid member and constituting the sole support for the ornamental member.

15. A bracelet comprising two rigid members hinged together at one end, clips each comprising an ornamental member and a member hinged thereto for attaching it to a fabric, and rigid means carried by the free ends of the bracelet members to removably support the clips.

ALFRED PHILIPPE.
